UNITED STATES PATENT OFFICE.

KARL EDWARD ANDERSON, OF CHICAGO, ILLINOIS.

MATERIAL HOLDER.

Application filed March 9, 1927. Serial No. 173,854.

My invention relates to a material holder, and the object of my invention is to provide a material holder which is capable of securing a can of roofing cement and a box of roofing nails within the usual opening provided in a roll of roofing material, building paper or the like.

It has been customary heretofore to place the can of cement and box of nails loosely within the opening through the roll of roofing, in such a way that they would roll and tumble about and become broken, in which case the cement would be wasted and the nails would damage the roofing material.

It has been necessary when using the old method, to provide discs in the ends of the roll connected by a wire for preventing the materials from falling out of the opening, but by the use of my invention it is unnecessary to employ end discs and the connecting wire, and the expense thereof is accordingly eliminated.

My invention will be best understood by reference to the accompanying drawing forming a part of this specification and in which,

Figure 1 is a perspective view of the material holder incorporating my invention and showing a can of cement secured therein.

Figure 2 is a partial plan view of a stamping of sheet metal from which the one portion of my invention is constructed.

Figure 3 is a plan view of a spring wire suitably shaped for use in my invention.

Figure 4 is a plan view of a modified form of spring adapted for a similar use.

Figure 5 is an elevational view of a roll of roofing partly in cross section and showing my invention also in cross section assembled therein.

In the drawing and for the purpose of illustration I have shown the preferred embodiment of my invention in which numeral 5 represents a roll of roofing material partly broken away and partly in cross section, and composed of a plurality of layers 6. The roll of roofing is provided in the usual way with an opening 7 therethrough, in which is assembled my invention 9, which is adapted to hold in position a can of cement 10 and a box of nails 11 interposed between the guard members 12.

The members 12 and the bottom member 13 are made up from a stamping of sheet metal which is shown in Figure 2, lying flat before it is bent into the position shown in

Figure 1. This stamping is provided with suitably shaped apertures 14 which, when the side members 12 are positioned as shown in Figure 1, provide rounded corners for the members 12 and 13, adjacent the lower rim of the can of cement, thereby, eliminating sharp corners which might damage the roofing material.

The member 13 positioned beneath the can 10 is flat as shown in Figures 2 and 5, and the side members 12 are curved so as to fit against the roofing material without presenting any sharp edges wherever said members happen to engage said roofing material. The shape of members 12 also aid in holding can 10 in position.

Ear members 15 or provided with openings 16 through which a relatively stiff spring wire 17 may be passed as best shown in Figure 1. Said ears 15 are punched out of the side members 12 and are adapted to engage the upper rim of the can of cement for aiding in holding the same in place. The upper end of said ears are adapted to engage the sides of said box of nails 11 for holding it in place as shown in Figure 5.

The spring wire 17 is held in engagement with the top of said can of cement by means of ears 15, and the upper end of members 12 constitute means for guarding or protecting the layers of roofing material 6 from being damaged by said spring 17. The upper end 18 of said side guarding members 12 is curved inwardly as shown in order that it may be drawn through the opening 7 without presenting any sharp corners or rough edges to the inner layers 6 and it, thereby, prevents damage to said roofing material.

It is obvious that the side members 12 and consequently the entire assembly 9 is held in position by means of static friction on the inner side of the opening 7, and it is obvious that said roofing material may engage members 12 practically the whole length thereof, providing the opening 7 is of the proper size to snugly fit said members. The spring member 17 is adapted to yieldingly hold said side guarding members 12 against the roofing material and is adapted to automatically adjust said members to accommodate variations in the size of said opening.

On the upper extremity of spring member 17 is provided upwardly extending prongs 19 which may be engaged by any suitable means for compressing said members toward each other to aid in positioning the assembly.

9 within the opening 7. Provided near the upper end of said member 17 are horizontal portions 20 which may be engaged by suitable means for forcing said assembly 9 into 5 the opening 7 and more particularly for withdrawing said assembly 9 from the opening 7 as will be readily apparent.

In Figure 4 is shown a modification 17' of the spring member 17, which is bent inwardly at a point 21 and again assumes a 10 position parallel with the opening 7 above the point 22 so that it will not engage members 12 above the point 21, and as a result this lengthened spring member 17' may be 15 used with the same side members 12 as that provided with the usual form of spring member 17.

The member 17' is adapted to accommodate a much longer box of nails than is the 20 member 17.

While I have described my invention in its preferred form it is apparent that many variations may be made herein without departing from the spirit of the invention. I 25 do not, therefore, wish to be limited to the precise details of construction set forth, but desire to avail myself of such variations and modifications as come within the scope of the appended claims.

30 I claim as my invention:

1. A device of the class described adapted to be inserted in an opening through a roll of roofing material, having means for holding a can of cement therein; additional 35 means for individually holding a box of nails therein and means for frictionally engaging the walls of said opening and spring means for increasing and maintaining said frictional engagement.

40 2. A device of the class described comprising a metal stamping adapted to be inserted in an opening through a roll of roofing material; said stamping having a flat portion adapted to have a can of cement positioned 45 thereon; said stamping having side members adapted to engage the walls of said opening and spring means for yieldingly maintaining said members in engagement with said walls.

50 3. A device of the class described comprising a metal stamping adapted to be inserted in an opening through a roll of roofing material; said stamping having a flat portion adapted to have a can of cement positioned 55 thereon; apertures in the sides of said stamping which provide rounded corners for said flat portion; the end portions of said stamping being bent upwardly; spring means for frictionally retaining said device 60 in position; said upwardly extending members providing means for protecting said roofing material from direct contact with said spring means.

65 4. A device of the class described comprising a metal stamping adapted to be in-

serted in an opening through a roll of roofing material; said stamping having a flat portion adapted to have a can of cement positioned thereon; said stamping having side members adapted to engage the walls of said 70 opening and spring means for yieldingly maintaining said members in engagement with said walls; means integral with said side members, for engaging the top edge of said can; said means adapted to hold said 75 spring means in engagement with said can.

5. A device of the class described comprising a metal stamping adapted to be inserted in an opening through a roll of roofing material; said stamping having a flat portion adapted to have a can of cement positioned thereon; said stamping having side 80 members adapted to engage the walls of said opening and spring means for yieldingly maintaining said members in engagement with said walls; prongs on said spring means by which said spring means is adapted to be compressed.

6. A device of the class described comprising a metal stamping adapted to be inserted in an opening through a roll of roofing material; said stamping having a flat portion adapted to have a can of cement positioned thereon; said stamping having side 90 members adapted to engage the walls of said opening and spring means for yieldingly maintaining said members in engagement with said walls; horizontal members on said spring means for withdrawing said device from said opening and for retaining a box 100 of roofing nails within said opening.

7. A device of the class described comprising a metal stamping adapted to be inserted in an opening through a roll of roofing material; said stamping having a flat portion adapted to have a can of cement positioned thereon; said stamping having side members adapted to engage the walls of said opening and spring means for yieldingly maintaining said members in engagement 110 with said walls; means integral with said side members for engaging the top edge of said can; said means adapted to hold said spring means in engagement with said can; prongs on said spring means by which said 115 spring means is adapted to be compressed.

8. A device of the class described comprising a metal stamping adapted to be inserted in an opening through a roll of roofing material; said stamping having a flat portion 120 adapted to have a can of cement positioned thereon; said stamping having side members adapted to engage the walls of said opening and spring means for yieldingly maintaining said members in engagement with said walls; prongs on said spring means by which said spring means is adapted to be compressed; horizontal members on said spring 125 means for withdrawing said device from said opening.

9. A device of the class described comprising a metal stamping adapted to be inserted in an opening through a roll of roofing material; said stamping having a flat portion adapted to have a can of cement positioned thereon; said stamping having side members adapted to engage the walls of said opening and spring means for yieldingly maintaining said members in engagement with said walls; means integral with said side members for engaging the top edge of said can; said means adapted to hold said spring means in engagement with said can; horizontal members on said spring means by means of which said device may be withdrawn from said opening.

10. A device of the class described comprising a metal stamping adapted to be inserted in an opening through a roll of roofing material; said stamping having a flat portion adapted to have a can of cement positioned thereon; said stamping having side members adapted to engage the walls of said opening and spring means for yieldingly maintaining said members in engagement with said walls; means integral with said side members for engaging the top edge of said can and for retaining a box of nails therein between; said means adapted to hold said spring means in engagement with said can; prongs on said spring means by means of which said spring means is adapted to be compressed for withdrawing said device from said opening; horizontal members on said spring means for retaining a box of nails within said opening.

11. A device of the class described adapted to be inserted in an opening through a roll of roofing material, comprising a stamping of sheet metal, providing a flat member adapted to have a can of cement positioned thereon; said flat member having rounded corners; said stamping having portions extending upwardly by the sides of said can, and being channelled to aid in retaining said can therein between; ear members punched out of said upwardly extending members for engaging the upper edge of said can; said ear members having openings there-

through for receiving a spring member, 50 which engages the upper end of said can, and the inner sides of said upwardly extending channelled members, and forcing them into frictional engagement with the walls of said opening; said upwardly extending members adapted to protect said roofing material from direct contact with said spring means, and having curved portions on the extreme upward ends thereof for preventing contact with and damage to said roofing material.

12. A device of the class described adapted to be inserted in an opening through a roll of roofing material, comprising a stamping of sheet metal, providing a flat member adapted to have a can of cement positioned thereon; said flat member having rounded corners; said stamping having portions extending upwardly by the sides of said can, and being channelled to aid in retaining said can therein between; ear members punched out of said upwardly extending members for engaging the upper edge of said can; said ear members having openings therethrough for receiving a spring member, which engages the upper end of said can, and the inner sides of said upwardly extending channelled members, for forcing them into frictional engagement with the walls of said opening; said upwardly extending members adapted to protect said roofing material from direct contact with said spring means, and having curved portions on the extreme upward ends thereof for preventing contact with and damage to said roofing material;

prongs on said spring means, by means of which said spring means is adapted to be compressed; means adjacent said prongs for withdrawing said device from said opening; the upper end of said ears engaging a box 90 of nails; said spring means extending partially around said box of nails, and said withdrawing means adapted to prevent said box from falling out of said opening in said roll.

In testimony whereof I have signed my name to this specification.

KARL EDWARD ANDERSON.
